CLAIM

The ornamental design for a garment steamer, as shown and described.

DESCRIPTION

FIG. 1 is a front perspective view of a garment steamer showing my new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof; and

FIG. 7 is a bottom plan view thereof.

The electric cord shown broken away in FIGS. 2, 4, 5, 6 and 7 for ease of illustration and is understood to represent indeterminate length.

FIG. 1.

FIG. 2.

FIG. 5.

FIG. 3.

FIG. 4.

FIG. 6.

FIG. 7.
